UNITED STATES PATENT OFFICE.

JOHN MINOR BOTT'S LEWIS, OF LYNCHBURG, VIRGINIA.

ANIMAL-STANCHION.

1,314,880.

Specification of Letters Patent.

Patented Sept. 2, 1919.

Application filed July 29, 1918. Serial No. 247,297.

To all whom it may concern:

Be it known that I, JOHN M. B. LEWIS, a citizen of the United States, residing at Lynchburg, in the county of Campbell and State of Virginia, have invented certain new and useful Improvements in Animal-Stanchions, of which the following is a specification.

My invention relates to improvements in animal stanchions.

Important objects of the invention are to provide a stanchion of the above mentioned character having; arms with the middle portions of the arms out of the transverse vertical plane of the lower portions thereof, when the arms are closed and within the transverse vertical plane when opened; means to automatically cause the stanchion to assume a predetermined transverse position when removed therefrom; adjustable means for supporting the arms of the stanchion, to shift them forwardly or rearwardly; means for adjusting the arms of the stanchion toward and away from each other when closed; simple and reliable means for opening and closing the stanchion and serving to lock the same in the closed and opened positions; flexible rotatable supporting means at one end of the stanchion and flexible anchoring means at the other end.

Other objects and advantages of the invention will be apparent during the course of the following description.

35 In the accompanying drawings, forming a part of this specification and in which like numerals are employed to designate like parts throughout the same,

Figure 1 is a side elevation of a stanchion embodying my invention, parts being broken away,

Fig. 2 is a longitudinal sectional view taken on line 2—2 of Fig. 1,

Fig. 2^a is a side elevation of the lower end of the stanchion, showing adjustable means for connecting the bottoms of the arms,

Fig. 3 is a plan view partly in horizontal section of a stanchion showing the same closed,

Fig. 4 is a side elevation of the upper end thereof, parts being in section, and parts broken away,

Fig. 5 is a plan view partly in section of the stanchion showing it open,

Fig. 6 is a detail section taken on line 6—6 of Fig. 3,

Fig. 7 is a horizontal sectional view taken on line 7—7 of Fig. 4,

Fig. 8 is a vertical sectional view taken on line 8—8 of Fig. 7,

Fig. 9 is a similar view taken on line 9—9 of Fig. 4, and,

Fig. 10 is a detail horizontal section taken on line 10—10 of Fig. 8.

In the drawings wherein for the purpose of illustration is shown a preferred embodiment of my invention, the numeral 15 designates my stanchion as a whole, comprising

upstanding tubular arms 16, as shown. 70

Each arm 16, as more clearly shown in Fig. 2, embodies a lower vertical portion 17, and the arm is bent at a point near its center, as

shown at 18, providing an upper portion 19, arranged forwardly of the lower portion 17. 75

When the arms 16 are in the closed position, the upper portions 19 are arranged in a transverse vertical plane in advance of the transverse vertical plane of the lower portions 17, and when the arms 16 are swung to 80

the open position, the upper and lower portions thereof are arranged in the same vertical transverse plane. Arranged near and beneath the lower ends of the arms 16 is a

U-shaped yoke or member 20, provided at 85

its ends with vertical reduced portions 21, shown more clearly in Figs. 8 and 10. These

reduced portions 21 are cylindrical and are

pivoted within the lower ends of the tubular arms 16. The extensions 21 are provided 90

with diametrically oppositely arranged seg-
mental openings 22, receiving transverse

pins 23, attached to the lower ends of the arms 16. It is thus apparent that each arm 95

has a pivotal connection with the U-shaped member or yoke 20.

A flexible anchor 24, such as a chain, is secured to the yoke 20, as shown at 25 and to the curb 26, of the floor of the stall. For-
wardly of the curb 26 is a manger 27, and 100
rearwardly of this curb is a litter gutter 28,
as is well known.

In Fig. 2^a, I have shown a different form of connecting means for the lower ends of the arms 16. In this figure, a transverse 105
member 29 is provided, having an eye 30,

swiveled thereto for connection with the flexible anchor 24. One end of the transverse member 29 projects into an elbow 31, and is bolted or riveted thereto. One arm 16 is pivoted within the upper end of the elbow 31 and is provided with the transverse pin or bolt 23, shown clearly in Fig. 10. The pin or bolt 23 projects through and operates within segmental slots 32, whereby the arm 16 is free to turn, as explained in connection with Fig. 1. The numeral 33 designates a T-coupling, and the transverse member 29 is longitudinally adjustably mounted within the horizontal portion of the T-coupling. This T-coupling is provided with openings for the reception of a bolt 34, adapted for insertion within a selected opening 35. The vertical portion of the T-coupling 33 pivotally receives the lower end of the other arm 16. This arm carries the transverse bolt or pin 23, operating within diametrically oppositely arranged slots 36, for effecting a pivotal connection between the arm 16 and the T-coupling 33. It is thus apparent that adjustable means are provided whereby the lower ends of the arms 16 may be shifted toward and away from each other.

Disposed at the upper ends of the arms 16 are cranks 37, having reduced extensions 38 (see Fig. 4) projecting into the upper ends of the tubular arms 16 and held therein by bolts or rivets 39, whereby these cranks are adapted to support and turn the arms 16 upon their longitudinal axes. The cranks 37 have their upper ends forked, providing ears or knuckles 40 and crank extensions 41. Arranged between the elements 40 and 41 are horizontal supporting arms 42, which are horizontally angularly adjusted for shifting the entire stanchion forwardly and rearwardly with respect to the elements 40 and 41, by bolts 43 or the like. At their inner ends, the arms 42 are provided with flat-heads 44, having openings 45, provided with recesses or notches, whereby these openings are adapted for the reception of a ribbed or toothed member 46. This ribbed or toothed member is rigidly secured to a suspension pin 47 and is preferably integral therewith. The toothed member 46 is provided near its lower end with a transverse opening for receiving a pin 48, and a washer 49 is disposed between this pin and the lower head 44. It is thus apparent that the pin 48 and associated elements serve as a means to lock the heads 44 together, whereby the arms 42 may be angularly adjusted. The lower head 44 has a segmental opening 50 (see Fig. 9), receiving a pin 51, having a screw-threaded shank 52 fitted within a screw-threaded opening 53, formed in the upper head 44.

The suspension pin 47 is provided at its upper end with a transverse opening receiv-

ing a transverse pin 54, operating upon a supporting block 55, having an opening 56 formed therein, pivotally receiving the suspension pin 47. The block 55 is provided upon its upper face with oppositely arranged cam faces 57, serving to return the stanchion to the transverse position, when removed therefrom. The block 55 is supported by arms 55', rigidly secured thereto, and carried by a plate 58, strapped to a horizontal support 59, by U-shaped bolts 60 or the like.

An arm 61 is rigidly secured to the suspension pin 47 and has a trunnion 62 rigidly secured thereto. A combined operating and locking lever 63 is pivoted between its ends, as shown at 64, upon the trunnion 62. This combined operating and locking lever is provided upon opposite sides of its pivot with a plurality of transverse openings 65, and eye-bolts 66 are adapted for insertion within selected openings 65. Links 67 are pivoted to the eye-bolts and to the free ends of the crank extensions 41. The function of having the eye-bolts 66 adjustable upon the lever 63 is to provide means whereby the distance between the upper ends of the arms 16, when closed, may be changed. In Fig. 4, the arms are shown as closed, and in this position, the lever 63 and associated elements 95 serve to lock the same closed, as the eyes 66 are slightly below the pivot 64. When the lever is swung to the left so that the arms 16 are opened, they are locked in this opened position by the lever 63, since the eyes 66 are 100 still slightly beneath the pivot 64.

When the arms 16 are closed, the upper portions 19 thereof are disposed in the rear of the lower portions 17. When the cow is standing, and eating from the manger 27, 105 these upper portions cause her to move rearwardly. When she lies down, the lower portion 17 causes her to move forwardly.

When it is desired to open the stanchion, the lever 63 is swung to the left, thereby 110 turning the arms 17 upon their longitudinal axes. The upper portions 19 are thereby swung open. When in the open position, the cow may conveniently enter the stanchion, and the pin 54 and cam faces 57 retain 115 the open stanchion in the proper transverse position when shifted therefrom.

It is to be understood that the form of my invention herewith shown and described is to be taken as a preferred example of the 120 same and that various changes in the shape, size, and arrangement of parts may be resorted to without departing from the spirit of my invention, or the scope of the subjoined claims.

Having thus described my invention, I claim:

1. In an animal stanchion of the character described, a pair of upstanding arms having the upper portions thereof arranged 130

- in a different vertical plane from their lower portions when the arms are closed, the upper portions of said arms being spaced when closed, said arms being permanently 5 free to turn upon their longitudinal axes, and means connecting the arms for turning the arms upon their longitudinal axes to open and close them.
2. In an animal stanchion of the character described, a pair of upstanding arms having their upper portions off-set laterally with relation to the lower portions, said upper portions of the arms being spaced when the arms are closed, means connecting the lower 10 ends of the arms, a support having permanently free pivotal connection with the same, and means connecting the arms for turning the arms upon their longitudinal axes to open and close them.
- 20 3. In an animal stanchion of the character described, a pair of upstanding arms having portions thereof laterally off-set, said offset portions being spaced when the same are closed, a transverse member having pivotal connection with the lower ends 25 of the arms so that the arms are free to turn upon their longitudinal axes with relation to the member, means to support the upper ends of the arms so that they are permanently free to turn upon their longitudinal axes, and means connecting the arms to turn the arms upon their longitudinal axes to open and close them.
4. In an animal stanchion of the character described, a pair of upstanding arms having portions thereof laterally off-set, a pivoted supporting element to turn in an approximately horizontal plane having permanently free pivotal connection with the 35 upper ends of the upstanding arms, a longitudinally adjustable device having pivotal connection with the lower ends of the upstanding arms, and adjustable means connected with the upper ends of the arms to 40 vary the distance between the same when closed and secured to the pivoted supporting element.
- 45 5. In an animal stanchion of the character described, a pair of upstanding arms having laterally off-set portions which are spaced when the arms are closed, a member having pivotal connection with the lower ends of the arms, means to support the upper ends of the arms, and means serving to 50 turn the arms upon their longitudinal axes 55 to opened and closed positions and to lock the same in such positions.
6. In an animal stanchion of the character described, upstanding arms having laterally off-set portions, means connecting the lower ends of the arms, means for supporting the upper ends of the arms, cranks connected with the upper ends of the arms to turn the same upon their longitudinal axes, a lever pivotally connected between its ends 60 with the supporting means, and links pivotally connected with the lever upon the opposite sides of its pivot and with the cranks.
7. In an animal stanchion of the character described, upstanding arms having laterally off-set portions, a member pivotally connected with the lower ends of the arms, supporting means connected with the upper ends of the arms, cranks connected with the arms to turn them upon their longitudinal 65 axes, a lever pivotally connected between its ends with the supporting means, links having their outer ends pivotally connected with the cranks, and pivot elements secured to the inner ends of the links and adapted for 70 connection with the lever at different distances from and upon the opposite sides of its pivot.
8. In an animal stanchion of the character described, upstanding arms adapted to 75 be moved to opened and closed positions, supporting arms connected with the upper ends of the upstanding arms and adapted to be angularly adjusted in a horizontal plane, and supporting means connected with 80 the supporting arms.
9. In an animal stanchion of the character described, upstanding arms having laterally off-set portions, means pivotally connected with the lower ends of the arms, a suspension element, a pair of arms, means to clamp the arms at different angular positions upon the suspension element, cranks connected with the upper ends of the arms and pivoted with the said pair of arms, and 85 means to swing the cranks.

In testimony whereof I affix my signature in presence of two witnesses.

JOHN MINOR BOTTS LEWIS.
